UNITED STATES PATENT OFFICE

JESSE EVERETT ESHBAUGH, OF FLINT, MICHIGAN

PROPAGANDA DISTRIBUTOR

Application filed March 10, 1932. Serial No. 598,068.

This invention relates to a device for distributing propaganda from a free balloon or other aerostat and provides a simple and inexpensive device of this class which will automatically initiate the distribution of the propaganda at a predetermined time and which will continue such distribution at an automatically regulated rate until the supply is exhausted.

- 5 10 15 20 25 30 35 40 45 50 55 60 65 70 75 80 85 90 95 100
- With the above in view, the invention consists of novel details of construction and in certain combination of parts, all of which are hereinafter fully described and specifically pointed out in the accompanying drawing, wherein:

Figure 1 is a view of a free balloon with the invention applied thereto, and

- Figure 2 is a vertical longitudinal sectional view of the propaganda distributor mechanism.

In the drawing, a free balloon is represented at 1 and includes the net 2 which supports the propaganda distributor mechanism. This mechanism is enclosed within a casing 3 open at the bottom and including a propaganda rack 4 having a plurality of depending partitions 5 complementally apertured at 6 to receive and guide the slidable rod 7 upon which are supported the propaganda material 8. The rod 7 is provided at one end with an eye 9 to which is connected one end of a flexible line 10, which is fastened at the other end to the rotatable shaft 11 of the rod-actuating means.

The shaft 11 is suitably journaled in the side walls of the casing 3 and carries a large, fixedly mounted, worm gear 12 in mesh with a driving worm 13. The driving worm is fixed on a shaft 14 rotatably supported in brackets 15 and 16 of the casing. Connected to the inner end of the worm shaft 14 are a plurality of rubber strands 17 which are also secured at their opposite ends, to a crank 18 by means of which the rubber strands are twisted in order to store up in said strands sufficient motive power to rotate the worm shaft 14. The crank 18 is rotatably supported in a bearing 19 in an end wall of the casing and is slidably axially so as to be moved into and out of the line of obstruction presented by

the stop pin 20. Springs or other torque means may be substituted for the rubber strands, if desirable, for effecting rotation of shaft 14.

The worm gear 12 and shaft 11 are normally held against rotation by means of a fusible tie-bar 21 secured at one end to the side of gear 12 and at the other end being fastened to a convenient part of the casing. Integral with and depending from the intermediate portion of the tie-bar 21 is a fuse 22 which, when ignited, burns and melts the tie-bar, thus releasing the rod-actuating mechanism. The length of the fuse 22, which is lighted before the balloon leaves the ground, determines the period of time elapsing before the device starts operating.

For the purpose of creating a braking action or a resistance against a too rapid rotation of the worm 13, a fan 23 is fixed to the outer end of the worm shaft 14 and is located within an open tube 24. By employing a fan of the proper size and pitch, the rate of distribution of the propaganda may be regulated to any desired degree.

The operation of the device is as follows: The propaganda to be distributed is in sheet form apertured at 25 complementally with the apertures 6 in the partitions 5 of the rack 4 so that the sheets may be threaded on the rod 7 as shown in the drawing. The crank 18 is then shifted outwardly of the casing to clear the stop pin 20 and rotated to twist the rubber strands 17, subsequent to which the crank is shifted inwardly to re-engage the stop pin from the side thereof preventing reverse rotation of the crank tending to unwind or untwist the rubber strands. The fuse 20 is lighted and the balloon released for ascent. The balloon rises for a predetermined length of time before the burning fuse severs the tie-bar and releases the worm gear 12. When this occurs, the previously twisted rubber strands 17 act upon the worm shaft 14 to rotate the same together with the worm 13 and the fan 23; the fan acting as an air brake and furnishing the necessary resistance to limit the speed of rotation of the worm 13. The worm gear 12 is rotated at a slower rate of speed by the worm 13 and turns the shaft

11 in a direction to slowly wind the flexible line 10 around the shaft, causing the rod to be withdrawn gradually from the apertures of the propaganda sheets and thus permitting them to drop successively from the rack until the supply is exhausted.

It is to be understood that the foregoing describes but a single application of the invention and that the latter is not limited to 10 the exact construction herein described and illustrated but includes all such changes and modifications as properly fall within the limits and scope of the appended claims.

Having thus described the invention what 15 I claim is:—

1. A propaganda distributing device comprising the combination with an aerostat of means carried by the aerostat for discharging propaganda material during the flight of 20 the same, means normally holding the discharging means inactive, automatic means for releasing the holding means at a predetermined time, and means for regulating the rate of distribution of the propaganda.

2. A propaganda distributing device comprising the combination with an aerostat of means for supporting propaganda material, means for effecting release of the material from the supporting means, actuating means 30 for the said material releasing means, fusible means normally holding the actuating means inactive and including an ignitable fuse of a predetermined length, and an air brake for regulating the action of the actuating means 35 to control the rate of propaganda distribution.

3. A propaganda distributing device comprising the combination with an aerostat of fixed guides, a slidable rod in said guides, 40 propaganda sheets loosely supported on the said rod and between the said guides, and means for withdrawing said rod from engagement with the said guides and propaganda sheets for effecting distribution of the 45 latter.

4. A propaganda distributing device comprising the combination with an aerostat of fixed guides, a slidable rod in said guides, propaganda sheets threaded on the said rod 50 and between the said guides, and automatic means for withdrawing the said rod from engagement with the said guides and propaganda sheets.

5. A propaganda distributing device comprising the combination with an aerostat of relatively spaced guides, a slidable rod in said guides, propaganda sheets threaded on the portion of the rod between the guides, means for withdrawing the rod from engagement with the said guides and the propaganda sheets, and means for regulating the rate of withdrawal of said rod.

6. A propaganda distributing device comprising the combination with an aerostat of relatively spaced guides, a slidable rod in

said guides, propaganda sheet between the said guides and loosely mounted on the said rod, rod-moving means for withdrawing the rod from engagement with the said guides and the said propaganda sheets, and means for holding the said rod-moving means inactive for a predetermined period of time.

7. A device of the character described including a propaganda rack, a slidable rod disposed transversely of the same to receive thereon propaganda sheets, a twistable rubber strand, and mechanism intermediate said strand and said rod for moving said rod.

8. A device of the character described including a propaganda rack provided with a plurality of depending partitions, a freely slidable rod disposed transversely through said partitions, said rack being adapted to receive propaganda sheets threaded on said rod between the said partitions, a twistable elastic strand and an actuating connection between said strand and said slidable rod for sliding said rod.

9. A device of the character described including a propaganda rack provided with a plurality of depending partitions having complementary apertures, a freely slidable rod disposed transversely through said partitions, said rack being adapted to receive propaganda sheets threaded on said rod between the said partitions, a rotatable shaft, means connected to said shaft and said rod for moving said rod, a gear on said shaft, a worm meshing with the gear and a twistable rubber strand for driving the worm.

10. A device of the character described including a propaganda rack provided with a plurality of depending partitions having complementary apertures, a freely slidable rod disposed transversely through said partitions, said rack being adapted to receive between the said partitions thereof propaganda sheets threaded on said slidable rod, a rotatable shaft, a flexible line connecting said slidable rod and said shaft, a gear on said shaft, a worm meshing with the gear, a twistable rubber strand for rotating the worm and a time fuse normally holding the gear against rotation.

11. A device of the character described including a propaganda rack provided with a plurality of depending partitions, a freely slidable rod disposed transversely through said partitions and the said rack being adapted to receive propaganda sheets threaded on said rod between said partitions, a rotatable shaft, a flexible line connecting said slidable rod and said shaft, a gear on said shaft, a worm meshing with the gear, a shaft for said worm, a crank, a twistable elastic connection between the worm shaft and the said crank, means providing resistance to the rotation of the worm, and a time fuse normally holding the gear against rotation.

12. A device of the character described

- including a propaganda rack provided with a plurality of depending partitions, a freely slideable rod disposed transversely through said partitions, said rack being adapted to receive propaganda sheets threaded on said rod between said partitions, a rotatable shaft, a flexible line connecting said slideable rod and said shaft, a gear fixed on said shaft, a worm meshing with the gear, a shaft for said worm, 5 a crank, a twistable elastic strand connected to the shaft of the worm and to the said crank, a fan on the worm shaft and a time fuse for holding the gearing inactive until a predetermined time.
- 10 13. A device of the character described including a propaganda rack provided with a plurality of depending partitions having complemental apertures, a rod extending transversely through said partitions and 20 freely slideable in said complemental apertures, said rack being adapted to receive propaganda sheets threaded on said rod between said partitions, a rotatable shaft, a flexible line connecting said slideable rod and 25 said shaft, a large gear fixed on said shaft, a small gear meshing with the large gear, a shaft for said small gear, a crank, a twistable rubber strand connected to the shaft of the small gear and to said crank, a fan on 30 the shaft of said small gear, and a time fuse fixedly connecting said gearing to a stationary part of the device to hold the same inactive until released by the destruction of the fuse.
- 35 In testimony whereof I affix my signature.

JESSE EVERETT ESHBAUGH.
